UNITED STATES PATENT OFFICE.

ALBERT F. HERMAN, OF CLEVELAND, AND HORACE S. ELLSON, OF LAKewood, OHIO,
ASSIGNORS TO NATIONAL CARBON COMPANY, INC., A CORPORATION OF NEW
YORK.

CONDUCTIVE BRUSH AND METHOD OF SECURING ATTACHMENTS THERETO.

Application filed May 19, 1924. Serial No. 714,496.

To all whom it may concern:

Be it known that we, ALBERT F. HERMAN and HORACE S. ELLSON, citizens of the United States, residing at Cleveland and 5 Lakewood, in the county of Cuyahoga and State of Ohio, have invented certain new and useful Improvements in Conductive Brushes and Methods of Securing Attachments Thereto, of which the following is 10 a specification.

This invention relates to improvements in the attachment of metallic members to conductive brushes for dynamo electric machines. The invention comprises the casting 15 of a metallic cap or sheath about a portion of the brush, in such manner as to secure one or more flexible conductors or shunts in permanent, low resistance electrical contact with the brush. A finger piece 20 for lifting the brush, a rest for the spring hammer of the brush holder, or the like, may be similarly secured.

The invention will be further described in connection with the accompanying drawings, in which

Fig. 1 is a perspective view of a brush before the casting of the cap;

Fig. 2 is a similar view, partly broken away, showing the cap, shunts and finger piece in position;

Fig. 3 is a perspective view, partly broken away, illustrating another form of brush having an electroplated coating on one end; and

Fig. 4 is a view similar to Fig. 3, showing the completed brush.

Referring to Figs. 1 and 2, reference numeral 1 denotes a conductive brush which may be made of carbon, compacted metal powder, or other suitable material. The invention is particularly applicable to carbon brushes, as it provides a strong, low resistance connection without the necessity of drilling, riveting, tamping, or the like, to fasten the shunt to the brush. Such processes frequently result in breakage of carbon brushes.

The brush 1 has a reduced upper portion 2. Space for receiving the end of a shunt is provided by beveling a corner of the reduced portion. In the type shown, which is adapted to have two shunts 3 and 3' connected to it, spaces 4 and 5 are so provided. A groove 6 may be formed in the top of

the brush to receive the base of a finger 55 piece 7, or the like. This may be made of steel or iron, or of less rigid material, as a copper alloy. In the latter case suitable strengthening ribs or corrugations may be provided.

Openings 8 are preferably formed in the reduced portion of the brush. Some of the cast metal will flow into these openings and anchor the cap 9. The same result may be obtained in other ways, as by inclining the 60 walls of the reduced portion inwardly.

The brush 10 shown in Figs. 3 and 4 has a cast cap 11 of the type previously described. It is, however, secured to the brush by union with an electroplated coating 12 70 applied to the reduced portion 13. Openings to receive the metal may be provided as in Fig. 1, but they are unnecessary under most conditions. An electroplated coating of usual thickness is ordinarily adequate. 75

The cap may be formed of any suitable metal or alloy. Brass, aluminum-copper alloys, and the like, are especially adapted for this purpose.

The dies used for casting the cap may be 80 of the usual die-casting type. They are best arranged to receive the brush, shunts, and other attachments before the molten metal is applied. It is preferable to force the metal into the die under high pressure, 85 which may be of the order of 1200 pounds per square inch. In this way a very hard, closely adherent cap is obtained. The exterior of the applied metal will be substantially flush with the lower surfaces of the 90 brush, so that it may be inserted in the usual holders.

Brushes manufactured according to the present invention give excellent service. The shunt connections are substantially unaffected by vibration. The finger pieces are also securely retained. Since the end of the shunt is practically an integral part of the cap, and the cap has a large surface in intimate contact with the brush, the voltage 100 drop between brush and shunt is negligible. Particularly low resistance contacts are obtained when the cap is cast about an electroplated coating so as to coalesce therewith. We regard this embodiment of our invention as especially important.

It is to be noted that we eliminate solder, which has heretofore been used to secure

shunts to metal caps riveted, clamped, or cast on brushes. Soldered connections are ordinarily of relatively high resistance and are subject to failure if the brush becomes 5 abnormally hot, which may occur under certain service conditions. In the type of brush having metal cast about the end of a shunt inserted in a drilled opening, difficulty is encountered in drilling and the 10 metallic area in contact with the brush is low, as compared with the present construction.

The invention is not limited to the forms shown. Various modifications may be made 15 in the shape of the brushes, the number and arrangement of shunts, the method of depositing the metal, and the like. Such modifications are within the scope of the appended claims.

20. We claim:

1. In combination with a conductive brush, a conductor, and deposited metal upon at least a portion of the lateral exterior of said brush, said conductor having 25 an end embedded in said metal.

2. In combination with a conductive brush, a flexible conductor, and a cast metal cap about and integrally joined to a portion of the brush, said conductor having an end 30 embedded in the cap.

3. In combination with a conductive brush having an electroplated coating on a portion of its surface, a cast metal cap adherent to said coating, and a flexible conductor having an end embedded in the cap. 35

4. In combination with a conductive brush having an electroplated coating on a portion of its surface, a metallic cap having its inner surface coalesced with the coating, 40

and a flexible conductor having an end embedded in said cap.

5. In combination with a conductive brush, a cast metal cap integrally joined to said brush, and attachments embedded in said cap. 45

6. A conductive brush having a reduced upper portion, a corner of which is cut away to receive the end of a flexible conductor, and a cast metal cap integrally joined to said reduced portion and embedding said 50 conductor.

7. A conductive brush having a reduced upper portion, and a groove formed therein adapted to receive the end of an attachment, and a cast metal cap integrally joined to 55 said upper portion and holding the end of the attachment in contact with said brush.

8. Method of securing an attachment to a conductive brush, comprising depositing metal about an exterior portion of the brush and embedding an end of such attachment 60 therein.

9. Method of securing a flexible conductor to a conductive brush, comprising inserting an end of the conductor in a lateral opening 65 of the brush, and casting metal about such opening and a further portion of the brush.

10. Method of securing a flexible conductor to a conductive brush, comprising die casting a metal about a portion of the brush 70 and flexible conductor.

11. Method of securing a flexible conductor to a conductive brush, comprising placing the brush in a die, inserting an end 75 of a flexible conductor in a recessed portion of the brush, and forcing a molten metal into the die and about the brush and conductor.

In testimony whereof, we affix our signatures.

ALBERT F. HERMAN.
HORACE S. ELLSON.
